(57) CLAIM

The ornamental design for a putter head, as shown and described.

DESCRIPTION

FIG. 1 is a perspective view, from above and in front, of the putter head of the invention.

FIG. 2 is a top plan view thereof.

FIG. 3 is a bottom plan view thereof.

FIG. 4 is a side elevational view thereof from the side opposite that on which a shaft is mounted.

FIG. 5 is a side elevational view thereof from the side on which a shaft is mounted.

FIG. 6 is a back elevational view thereof; and,

FIG. 7 is a front elevational view thereof.

The broken line showing of the fragmented shaft is for illustrative purposes only and forms no part of the claimed design.
